BALL POINT PEN

John D. Currence, Bernardsville, and Edward J.
Egan, Basking Ridge, N. J.

Application December 26, 1950, Serial No. 13,595

Term of patent 14 years

(Cl. D74—17)

To all whom it may concern:

Be it known that we, John D. Currence and Edward J. Egan, citizens of the United States, residing at Bernardsville and Basking Ridge respectively, in the county of Somerset and State of New Jersey, have invented a new, original, and ornamental Design for Ball Point Pen, of which the following is a specification, reference being had to the accompanying drawing, forming part thereof.

The figure is a side perspective view of a ball point pen, showing our new design, the opposite side presenting substantially the same appearance as the side shown.

We claim:

The ornamental design for a Ball Point Pen, as shown and described.

JOHN D. CURRENCE.
EDWARD J. EGAN.
